UNITED STATES PATENT OFFICE.

ROBERT J. COPELAND, OF TORONTO, ONTARIO, CANADA.

BOOK COVER.

Application filed August 22, 1921. Serial No. 494,196.

To all whom it may concern:

Be it known that I, ROBERT JAMES COPELAND, a subject of the King of Great Britain, and resident of the city of Toronto, 5 county of York, Province of Ontario, in the Dominion of Canada, have invented certain new and useful Improvements in Book Covers, described in the following specification and illustrated in the accompanying drawings, that form part of the same.

The objects of this invention are, to provide a cover for books which are subject to considerable handling which will withstand the heavy service and will effectively protect 15 the leaves of the book.

The principal feature of the invention consists in the novel construction and arrangement of a plurality of sections of a tough, homogeneous material such as vulcanized 20 fibre assembled together in overlapping arrangement to produce a rigid cover structure having wear resisting edges.

In the drawings Figure 1 is a perspective view showing the panel partly broken 25 away.

Figure 2 is an enlarged detail of one of the corners of the frame illustrating the manner of interlocking the under side sections.

Figure 3 is an enlarged longitudinal section of the cover.

Figures 4 and 5 and 6 are enlarged perspective details of portions of the frame and the interlocking member.

The cover frame is formed of a plurality of sections of vulcanized fibre. The hinge strip 1 has secured to its under side a thinner strip 2 which is of greater width and projects forwardly forming a ledge 3. 35 This under strip is of lesser length than the strip 1 and abutting the ends of said under strip are the bottom side strips 4 which extend beyond the end edges of the hinge strip 1 and project forwardly.

Upper side strips 5 of equal thickness to the strip 1 and extending to the outer edge of the bottom strips 4, are arranged to abut the ends of the strip 1. The upper side strips are of lesser width than the bottom 50 side strips and said bottom strips thus form the side ledges 6.

A bottom end strip 7 of substantially equal width to the side strips extends between the outer ends of the bottom side strips and is here shown with tongue portions 8 interlocking with the corresponding

recesses 9 in the side strips. Similar interlocking tongues may be arranged to connect the bottom hinge strip and the side strips.

A top end strip 10 of similar dimensions to the top side strips is arranged upon the bottom end strip 7 at its outer edge thus leaving an end ledge 11 at the inner side thereof.

Corner blocks 12 of angular shape and of equal thickness to the top side and end strips complete the frame structure.

The various sections shaped as described are accurately fitted and may be rigidly secured together by riveting or in any suitable manner but I show herein a special manner of connecting same.

The under sides of the top strips and corner blocks are formed with a continuous groove 13 and into this groove is fitted a metal strip 14, which is preferably doubled and formed with pairs of lugs 15 projecting downwardly. These lugs extend through slots 16 cut in the bottom strip and are spread apart as shown in Figures 2 and 3. 80 The metal strips 14 rigidly are secured in the upper fibre strips by transversely arranged pins 15' inserted through the side walls.

This arrangement forms a very rigid 85 means of connecting the various sections and it also stiffens the whole structure.

Flat strips 17 preferably of sheet metal are arranged to re-enforce the joints between the several top sections and these are secured 90 by rivets extending through the top and bottom strips.

A panel 18 preferably formed of mill board is adapted to rest upon the ledges 3, 6 and 11 and to this panel is secured a smaller panel 19 fitting snugly between the bottom strips. The panel thus formed is securely riveted to the bottom ledge strips and the whole structure is thus rigidly 95 united.

The upper surface of the panel 18 may be depressed below the top of the frame to protect the facing material placed thereon if desired.

The vulcanized fibre is strong and durable 105 and is capable of receiving a polished finish and an article of excellent appearance as well as great strength and durability is produced.

What I claim as my invention is:—

1. A book cover comprising a frame composed of a plurality of sections of a tough

homogeneous material fitted together in superposed strips arranged to overlap, the lower strips projecting inwardly beyond the upper strips and forming ledges, and a panel having ledges fitting over the frame ledges and rigidly secured thereto.

2. A book cover comprising a hinge section formed of upper and lower strips the lower strip projecting beyond the front side forming a ledge, side sections formed of upper strips abutting the ends of the upper hinge strip and lower strips of greater width projecting inwardly and forming ledges, an end section formed in upper and lower strips the lower strip projecting inwardly to form a ledge, means for rigidly connecting the various strips and sections together, and a panel rigidly secured to said ledges.

3. A book cover comprising a frame composed of a plurality of sections of a tough homogeneous material fitted together in superposed strips arranged to overlap, one set of said strips having a continuous groove formed in the face abutting the other set of strips and the other set of strips having

slots therethrough arranged to register with the groove, a metallic strip rigidly secured in the continuous groove and connecting the members of the set and having projecting lugs adapted to extend through the slots in the other set of strips and to be locked in engagement therewith.

4. A book cover comprising a frame composed of a plurality of sections of a tough homogeneous material fitted together in superposed strips arranged to overlap, one set of strips having a continuous groove formed in the face abutting the other set of strips and the other set of strips having slots therethrough arranged to register with the groove, a metallic strip arranged in said groove and connecting the several grooved members, pins inserted transversely of the strips through said metal strip, and lugs on said metallic strip adapted to extend through the slots in the other set of strips and to be turned laterally thereunder to lock the strips together.

ROBERT J. COPELAND.
